UNITED STATES PATENT OFFICE.

JOHN R. STARK, OF NASHVILLE, TENNESSEE, ASSIGNOR, BY MESNE ASSIGNMENTS,
TO C. R. CLEMENTS, TRUSTEE, OF NASHVILLE, TENNESSEE.

ADJUSTABLE BED BOTTOM.

1,402,106.

Specification of Letters Patent. Patented Jan. 3, 1922.

Application filed December 21, 1916, Serial No. 138,241. Renewed June 14, 1921. Serial No. 477,603.

To all whom it may concern:

Be it known that I, JOHN R. STARK, a citizen of the United States, residing at Nashville, in the county of Davidson and State of Tennessee, have invented certain new and useful Improvements in Adjustable Bed Bottoms, of which the following is a specification.

The invention aims further to provide means whereby the sections however they may be adjusted may be quickly and rigidly secured against disarrangement without the necessity of employing tools of any character.

The invention also aims to provide means whereby the bed bottom proper may be adjusted forwardly or rearwardly along the side rails thereof at the point of connection designed for invalid use, and it is one aim of the invention to provide a bed bottom section which may be readily adjusted to suit either the convenience and comfort of the invalid, or to support the invalid in such various positions as may be desired by the physician or nurse.

Another aim of the invention is to provide a bed bottom of the class mentioned which may be readily assembled with the head and foot boards of any ordinary bedstead, the structure embodying side rails which correspond to the side rails of the ordinary bedstead and which at their ends are constructed in the usual manner to fit the corner sockets at the opposite sides of the said head and foot boards.

Briefly stated, the bed bottom embodying the present invention includes relatively adjustable head, foot and intermediate sections, and the invention aims to provide for adjustment of the head section to any desired position between the horizontal and vertical and to securely support the same, the adjustment being independent of the intermediate and foot sections.

The invention also aims to provide, if desired, for automatic adjustment of the foot and intermediate sections upon adjustment of one of the side rails of the bed bottom, of the head section so that if the patient is to occupy a substantially upright position in the said side rail; the bed the nurse or other attendant is required only to lift or swing upwardly the head section whatsover to the foot and intermediate sections.

Another aim of the invention is to provide for downward swinging of the foot section in any desired position of an adjustment, and, incidentally, the invention aims to provide for this adjustment either in conjunction with an adjustment of the head section or independently thereof.

The invention aims further to provide

means whereby the head section with the intermediate section may be raised or lowered, either similarly or relatively.

In the accompanying drawings:

Figure 1 is a vertical longitudinal sectional view through the bed bottom embodying the present invention, the same being shown in normal or horizontal position;

Fig. 2 is a similar view illustrating the foot and intermediate sections in normal position and the head section raised;

Fig. 3 is a similar view illustrating the corner sockets at the opposite sides of the said head and foot boards.

Fig. 4 is a top plan view of one side of the bed bottom;

Fig. 5 is a vertical transverse sectional view or the line 5-5 of Fig. 1, the bed bottom being omitted;

Fig. 6 is a vertical longitudinal sectional view through the locking means for holding the sections of the bed bottom in ad-

justed position;

Fig. 7 is a fragmentary perspective view of one of the side rails of the bed bottom;

Fig. 8 is a fragmentary top plan view of the said side rail;

Fig. 9 is a perspective view of one of the track members for holding the head section of the bed bottom in adjusted position;

Fig. 10 is a vertical transverse sectional view taken substantially on the line 10-10 of Fig. 2;

Fig. 11 is a perspective view of the support means for the head section of the bed bottom and for holding the said bed bottom;

Fig. 12 is a vertical sectional view through one of the legs of the bedstead illustrating the manner in which the same may be adjusted as to length for the purpose of raising or lowering the head or foot board.

110

In the drawings, the numeral 1 indicates in general the head board of a bedstead and 2 the foot board thereof.

The bed bottom embodying the present invention includes side rails which are here illustrated as of L-angle iron construction although they may be tubular or of any other cross sectional shape. In the present instance, however, each rail has an upstanding wing 3 and a horizontal wing 4 and the rails are provided at their forward and rear ends with the usual members 5 adapted to be fitted into the sockets of the usual corner fastenings 6 at the opposite sides of the head 10 and foot boards 1 and 2, it being understood that the side rails just described take the place of the side rails of the ordinary bedstead. For a purpose which will presently be explained the horizontal wing 4 of each side rail is cut away as indicated by the numeral 7, this cut away portion being located near the foot end of the rail, as clearly shown in Fig. 3 of the drawings, and in order that the gap formed by cutting away the said wings may be normally closed, there is provided in connection with each rail, a rail section or track member having an upstanding wing 8 and a horizontal wing 9. The wing 8 of each rail section or 20 track member extends beyond the wing 9 and is pivotally connected as at 10 with the upstanding wing 3 of the respective rail at the foot end of the cut away portion 7. It will be apparent by reference to Fig. 1 of the drawings that the rail section or track member may be swung upwardly so that the wing 9 will extend between the ends of the cut away portion of the wing 4 of the respective rail and close the gap formed by 30 cutting away the said wing 4, or, as illustrated in Figs. 3 and 7, of the drawings, the rail sections may be swung downwardly so that the wing 9 will occupy an inclined position with relation to the wing 4 of the respective rail. In order that each rail section may be held at the desired position of angular adjustment a brace arm 11 is pivotally connected at its head end, as at 12, to the wing 3 of the respective rail and this 40 arm is formed with a longitudinally extending slot 13. At its foot end the arm extends beside the wing 8 of the respective rail section and a clamping bolt 14 is fitted through the slot 13 and through the end of the wing 8 and has applied thereto a nut 15 which may be tightened for the purpose of binding the wing 8 and arm 11 when the rail section has been adjusted to the desired position.

The bed bottom proper comprises a head 60 section, indicated in general by the reference character A, an intermediate section indicated in general by the reference character B and a foot section indicated in general by the reference character C.

65 The head section A includes side members

which are indicated by the numeral 16 and which are preferably of L-angle iron construction and a connecting end member 17 also of angle iron construction. The side members 16 and connecting member 17 include vertical wings and horizontal wings which extend inwardly from the upper edges of the vertical wings, and riveted or otherwise secured to the undersides of the said horizontal wings of the side members 70 at their foot ends are short lengths of angle iron indicated at 18, each having a vertical wing 19 opposing and lying parallel to the vertical wing of the respective side member 16, as clearly shown in Fig. 5 of the drawings. A pivot pin 20 is fitted through each wing 19 and the vertical wing of the respective side member 16 and these pivot pins extend also through the upper ends of clamping heads 21. As will be apparent by reference to the drawings two of the heads 21 are provided and each head is formed with a recess 22 in its outer face to receive the horizontal flange 4 of that one of the side rails with which the head is assembled, each head 80 being further provided upon its said outer face and below the recess 22 with a clamping lip 23. A clamping screw 24 is threaded upwardly through each clamping lip 23 and is designed to bear against the lower side of 90 the horizontal wing 4 of the respective side rail and by tightening these clamping screws the heads may be held at any desired positions of adjustment in the length of the said side rails. It will now be understood that 100 when the clamping heads are secured in place the head section has, in effect, its side portions pivotally connected at their foot ends with the side rails of the bedstead so that the head section may occupy a horizontal position, as shown in Fig. 1 of the drawings, in which position its side members will rest upon the horizontal flanges of the side rails of the bedstead or it may be swung upwardly to a vertical position or some intermediate inclined position, as shown, for example, in Figs. 2 and 3 of the drawings. In order that the head section may be supported in any of its positions of angular adjustment means is provided which will 110 now be described. The means just mentioned includes a supporting member having spaced arms 25 and a connecting portion 26, the arms of the said member extending parallel to each other and the connecting portion 26 extending at right angles between the free ends of the said arms. The arms at their opposite ends are pivotally connected, as at 27, to the side members 16 of the head section A at a point between the 120 head and foot ends of the said section. The connecting portion 26 of the supporting member is designed to cooperate with rack members, which are mounted upon the side rails of the bedstead and one of these rack mem- 130

bers is clearly illustrated in Fig. 9 of the drawings, the same comprising a plate 28 having an upstanding flange 29, which is of rack formation, as clearly illustrated in the said figure. The plate 28 is provided with an upwardly offset laterally extending clamping lip 30 which is designed to rest upon the upper surface of the horizontal wing of the respective side rail and secured to or formed upon the underside of the plate 28 and projecting below the lip 30 is a pair of ears 31 through each of which is threaded a clamping screw, indicated by the numeral 32, it being understood that these ears 31 extend beneath the horizontal flange of the respective side rail and that the clamping screws 32 are to be tightened to bear against the undersides of the said horizontal wings and firmly clamp the rack members as a whole in place upon the said rails. By reference to Fig. 1, it will be observed that when the head section is lowered to horizontal position the supporting member which is pivotally connected therewith will be housed within the section and will be out of cooperative relation to the rack members. However, as the head section is swung to upright position, as shown in Figs. 2 and 3 of the drawings, the connecting portion 26 of the supporting member will ride successively over the corresponding teeth of the rack members and when the head section has been brought to the desired position of adjustment it may be released and the connecting portion of the supporting member will then be in proper engagement with the rack members to firmly support the said head section in its position of adjustment. In order that the clamping heads 21 may be relatively braced and therefore in order that the pivoted ends of the side portions of the head section may be relatively braced, a cross bar 33 extends between the said clamping heads and this bar is provided with upturned ends 34, the extremities of which are secured to the said clamping heads. By forming the cross bar with the upstanding end portions 34, the main portion of the bar is located a sufficient distance below the surface of the bed bottom to insure against said surface coming in contact with the bar and discomforting the patient.

The intermediate section B includes side members 35 which are preferably of L-angle iron construction and which at their head ends are pivotally connected with the clamping heads 21 by means of the pivot pins 20 heretofore mentioned. The foot section of the bed bottom includes side members 36, which are also preferably of L-angle iron construction, and a connecting member 37, which extends between the foot ends of the said side members 36. The vertical wings of the side members 35 and 36 of the intermediate and foot sections respectively, over-

lap and are pivotally connected by the ends of a bracing rod 38, the end portions of the said rod being bent upwardly, as at 39, and thence turned laterally and fitted through openings formed in the said overlapped ends of the said side members 35 and 36 for the purpose stated. It will now be apparent that the intermediate and foot sections may be relatively angularly adjusted or that the foot section may be angularly adjusted independently of the intermediate section. In order that the foot corners of the foot section may readily ride over the horizontal flanges of the side rails, brackets 40 are secured to the under side of the horizontal wing of the connecting member 37 and within these brackets and the vertical wings of the side members 36 of the said foot section are mounted spindles 41 supporting rollers 42, which rest upon the said horizontal flanges of the side rails for the purpose stated.

In order that the head, intermediate and foot sections may be held in positions of relative adjustment, each of the members 19 has secured to it a downwardly extended arm 43. Arms 44 are pivotally connected at their foot ends to the inner ends of the spindles 41 which thus serve not only as supports for the rollers 42, but also as pivotal connections between the arms 44 and the side members 36 of the foot section of the bed bottom. Each of the arms 44 is formed with a longitudinally extending slot 45 and means is provided for cooperation with the slotted portions of the arms 44 and with the lower ends of the arms 43, for holding these parts at adjustment, and, consequently, holding the head, intermediate, and foot sections of the bed bottom in positions of relative adjustment. The means above referred to is clearly illustrated in Fig. 6 of the drawings, and includes a rod 46 which is provided at one end with a head 47 and at its other end is threaded as at 48. This rod 46 is fitted through the lower ends of the arms 43 and through the slots 45 in the arms 44 and extends transversely beneath the bed bottom. Each of the arms 43 is provided in its said end with an opening 49 and fitted upon the rod 46 near each end thereof is a spacing collar 50 occupying the opening in the respective arm 43.

A washer 51 is fitted upon the rod between the head 47 thereof and the adjacent arm 44 and a washer 52 is fitted upon the rod between each spacing collar 50 and the respective arm 43, the collars 50 being, as shown in Fig. 6 of the drawings, of a length greater than the thickness of the respective arms 43. A washer 53 is fitted upon the rod 46 inwardly of each of the arms 43 and a sleeve 54 is fitted upon the rod 46 and at its ends abuts against the washers 53. The numeral 55 indicates a sleeve nut which is

threaded upon the end 48 of the rod 46 and this nut is provided with a transverse handle 56 whereby it may be conveniently and readily turned by hand. It will now be understood that when the nut 55 is loosened the head section may be adjusted independently of the foot section, or the foot section may be adjusted independently of the head section, the ends of the rod 46 riding in the slots 45 without interference. However, when either section has been adjusted to the desired position the same may be secured by tightening the sleeve nut 55 whereupon the washers 52 and 53 will be caused to bind the opposite sides of the arms 44 holding the parts in the desired position of adjustment. If, when the head, intermediate, and foot sections are in normal or horizontal positions, as shown in Fig. 1 of the drawings, the sleeve nut 55 is tightened, the three sections will be automatically relatively adjusted merely upon swinging movement of the head section for in this case if the head section be swung upwardly a pull will be exerted upon the arms 44 and as a consequence the head end of the foot section will be drawn forwardly and the foot and intermediate sections will buckle, or in other words, their mutually connected ends will rise. It will be understood, of course, that when the nut 55 is tightened the rod 46 is held fixed with relation to the arms 44 although the arms 43 are free to pivot about the said rod upon the spacing collars 50. This relative adjustment may take place while the foot end of the foot section occupies the normal plane of the bed bottom or the foot section may be caused to lower as shown in Fig. 3 of the drawings, and when it is desired to obtain this latter adjustment the nuts 15 will be loosened and the rail sections heretofore described will be swung downwardly to about the position shown in the said Fig. 3 and in Fig. 7, or more specifically speaking, to such position that the foot corners of the foot section or the rollers 42 will rest upon the wings 9 of the rail sections to support the foot section at the desired angle. In order to insure of relative automatic adjustment of all three sections of the bed bottom when the nut 55 has been tightened at the time the sections are as shown in Fig. 1 of the drawings, lugs 57 are secured to the vertical wings of the intermediate section 35 at the foot ends thereof and project below the lower edges of the said wings and by resting at their lower ends upon the horizontal wings 4 of the side rails of the bedstead serve to support the mutually connected ends of the side members of the intermediate and foot sections slightly elevated, or in other words, out of horizontal alinement. As a consequence, when a pull is exerted upon the arms 44 the sections B and C will be immediately elevated at their mutually connected ends.

The fabric of the bed bottom is indicated by the numeral 58 and may be of any of the ordinary constructions, the same extending the entire length and width of the head, intermediate and foot sections of the bed bottom and being stretched between the sides and ends of these said sections and connected to the horizontal wings of the angle iron members comprising the said sections. 70

In order that the head end and foot end of the bedstead as a whole may be vertically adjusted, each leg of the bedstead includes a section 59 fixed with relation to the head or foot board as the case may be, and a section 60 which is telescopically fitted therein and provided with a number of transverse openings 61 through which a pin 62 may be fitted interchangeably to engage the lower end of the fixed section 59, as clearly shown in Fig. 12 of the drawings. It will be understood that the head end and foot end of the bedstead may be independently or similarly adjusted, as desired. 80

Having thus described the invention, what is claimed as new is: 90

1. In a bed bottom structure, head, intermediate, and foot sections, the head and foot sections being independently adjustable, means directly hingedly connecting the foot and intermediate sections, means 95 for preventing the said sections assuming a position in alinement with each other whereby to normally break the joint between the sections, and connections between the said head and foot sections operable to automatically adjust the foot and intermediate sections upon manual adjustment of the head section. 100

2. In a bed bottom structure, head, intermediate, and foot sections, the said sections 105 being mutually hingedly connected, means supporting the adjacent ends of the head and intermediate sections and constructed for adjustable attachment to the side rails of a bedstead, a supporting member connected with the head section, and a member for cooperation therewith constructed for adjustable attachment to one of the said rails. 110

3. In a bed bottom structure, sections relatively angularly adjustable, rigid arms carried by one of said sections, arms pivotally connected with the other section and each formed with a slot, a rod extending through the rigid arms and through the slots in the 120 pivoted arms, clamping elements upon each end of the rod for coaction with the pivoted arms, and means operable to simultaneously cause coaction of the clamping elements with the said pivoted arms. 115

4. In a bed bottom structure, sections relatively angularly adjustable, rigid arms carried by one of said sections, arms pivotally connected with the other section and each formed with a slot, a rod extending 130

through the rigid arms and through the slots in the pivoted arms, clamping elements upon each end of the rod for coaction with the pivoted arms, and means located at one end of the rod operable to simultaneously cause coaction of the clamping elements with the said pivoted arms.

5. In a bed bottom structure, sections relatively angularly adjustable, rigid arms extending from one of said sections, arms pivotally connected with the other section and each formed with a slot, a rod extending through the rigid arms and through the slots in the pivoted arms and provided at one end with a head and threaded at its other end, a clamping element upon the rod between each pivoted arm and the respective fixed arm, a sleeve upon the rod bearing at its ends between the pivoted arms, and a clamping nut upon the threaded end of the rod.

6. In a bed bottom structure, head, intermediate, and foot sections, the foot and intermediate sections being directly hingedly connected, means for preventing the foot and intermediate sections assuming a position in mutual alinement whereby to normally break the joint between the sections, and means operable to automatically adjust the foot section upon manual adjustment of the head section.

7. In a bed bottom structure, spaced rails each provided with a gap, means adjustable to close the gap, and a foot section movable through the gap when open and angularly adjustable in planes below the said rails.

8. In a bed bottom structure, side rails each provided with a gap, bed bottom sections supported by the rails and mutually hingedly connected, one of said sections be-

ing adjustable with relation to the other and movable through the gap when the gaps are open, and means adjustable to close each gap.

9. In a bed bottom structure, head, intermediate, and foot sections, the said sections being relatively angularly adjustable, spaced rails supporting the said sections, each of said rails being provided with a gap, means adjustable to close each of said gaps, the foot section being arranged to move over and be supported by the foot rails and by the closing means for the gap when adjusted angularly in planes above the said rails and to pass through the gaps for adjustment in planes below the rails.

10. In a bed, the combination of a supporting frame having parts of its side bars cut-away, track members pivotally attached to said side bars at their rear ends, adjustable connections between the front ends of said track members and the side bars whereby to secure the track members in position to close the cut-away portions of the side bars, a seat section pivotally attached to the frame, and a foot section pivotally connected with the seat section and having one end free and arranged to ride upon the side bars of the frame and the said track members.

11. In a bed, spaced rails each provided with a gap, track members pivoted to the rails in position to close the gaps, means for securing said members in gap-closing position, and a foot section movable on the rails and the track members and through the gaps when the same are open.

In testimony whereof I affix my signature

JNO. R. STARK. [L.S.]
